COMBINED BOTTLE AND HOLDER

Paolo Garretto, Paris, France

Application September 9, 1950, Serial No. 12,113

Term of patent 14 years

(Cl. D58—8)

To all whom it may concern:

Be it known that I, Paolo Garretto, a citizen of the Italian Republic, residing at Paris, Seine, France, have invented a new, original, and ornamental Design for a Combined Bottle and Holder, of which the following is a specification, reference being had to the accompanying drawing, forming part thereof.

Fig. 1 is a top perspective view of a combined bottle and holder showing my new design; and

Fig. 2 is a vertical section through the holder with the bottle in side view.

I claim:

The ornamental design for a combined bottle and holder, as shown.

PAOLO GARRETTO.
